AIMÉ MARIN, OF VITRY-SUR-SEINE, FRANCE.

CAP FOR INCANDESCENT LAMPS.

1,141,400.

Specification of Letters Patent. Patented June 1, 1915.

Application filed July 8, 1913. Serial No. 777,017.

To all whom it may concern:

Be it known that I, AIMÉ MARIN, of 35 Avenue des Acacias, Vitry-sur-Seine, Seine, in the Republic of France, have invented a certain new and useful Cap for Incandescent Lamps, of which the following is a specification.

The caps of incandescent lamps are formed of a metal socket which is closed, on the side away from the bulb, by a disk of insulating material carrying the contacts against which abut the metallic conductors connected to the lamp filament. The present practice is to make the cap of copper, and the insulating disk of glass, cast in the base of this cap. From the standpoint of economy it would be advantageous to use aluminium in place of copper for the socket of the cap. Making the same of copper is expensive because it cannot be shaped in one pass, and the metal has to be annealed after each pass; whereas aluminium, on the contrary, enables the cap to be shaped without annealing. Owing to its ductility the aluminium may be thinner than the copper—which means a saving. Moreover, aluminium does not oxidize; it is more sightly; and being light, is advantageous in respect of carriage and import duty. Nevertheless, aluminium has not, up to the present, been used for making the caps of electric lamps, the reason being that it does not permit the use of the insulating disk of molten glass, the high temperature of which is injurious to the metal. Attempts have also been made to fill up the bottom of the shaped cap by an insulating disk of porcelain; but such porcelain disks are difficult to fix. The beveling of the metal cap on to the disk is a frequent cause of breakage in the latter; and besides it is impracticable to obtain these porcelain disks of perfectly identical dimensions, their method of manufacture preventing absolute regularity, and they do not allow a tight joint to be made with the metal by beveling. In these conditions the production of the lamp caps is very difficult.

This explanation will enable the advantages to be appreciated which are afforded by making lamp caps in accordance with the invention forming the subject of the present application, said invention comprising: (a) the forming of the caps of aluminium, without annealing between the stages of the shaping process; (b) the closing of the

lower portion of this metal cap by a disk, which is made beforehand and is not poured like molten glass, and differs from the porcelain disk inasmuch as it cannot be broken in the operation of beveling the metal of the cap, being made of strong, unbreakable cardboard. Moreover the cardboard washer is securely attached to the base of the aluminium cap, because while being provided on its outer face with a circular groove to house the beveled metal of the cap, its inner face is provided with recesses for receiving the inner ends of the pins or gudgeons which, as in the existing electric lamps, serve to secure the incandescent lamps in the sockets of the lamp holders, on the bayonet catch principle. In consequence of this arrangement, the cardboard disk which fills up the metal cap, is held securely in the latter and cannot turn in the same during the operation of beveling the aluminium into the circular groove on the outer face of said disk. It should also be pointed out that this perfectly cylindrical cardboard disk, produced by punching and stamping, always has the same very regular shape, which cannot be obtained in the case of porcelain or other ceramic material.

The accompanying drawing illustrates, by way of example, how this production of aluminium caps, closed at the base with cardboard, is accomplished in practice.

Figure 1 is a transverse section of the cap with the disk removed. Fig. 2 is a side elevation of the disk. Fig. 3 is a bottom plan view of the disk. Fig. 4 is a transverse section of the disk. Fig. 5 is a top plan view of the disk. Fig. 6 is a side view of one of the pins or gudgeons. Fig. 7 is a view similar to Fig. 1, with the disk in place. Fig. 8 is a section similar to Fig. 7, the cap being turned through an angle of 90°.

An aluminium cap *a* (Fig. 1) is shaped in one or more stages, but without annealing the metal. The gudgeons *b*, which serve to fix the incandescent lamp in the lampholder on the bayonet-catch principle, are secured. These gudgeons are made as shown in the separate view of one of them in Fig. 6, namely of an aluminium rod *b* provided with a collar *c* in one piece with said rod, and adapted to bear on the inner side of the metal socket. The inner ends of these gudgeons projecting on the inner side of the metal of the cap, serve as stops for holding the closing disk of cardboard.

An insulating cardboard disk is shown separately as an outside view, in Fig. 2; as a plan, viewed from above, in Fig. 3; as a section, along the line M M of Fig. 3, in Fig. 4; and as a plan, viewed from below, in Fig. 5. This disk *c* is provided with a circular groove *d* on its outer face, and a slight ridge *e* on the inner face. This ridge *e* is provided with two diametrically opposite recesses *f* intended to serve as lodgments for the ends of the gudgeons *b* which project into the interior of the metal cap. Two holes *g* are intended for the passage of the metallic conductors to which the ends of the filament in the bulb are connected. On its outer face, the disk is provided with two elongated recesses *h* *h*, intended to accommodate small metal plates *k* *k* (see Fig. 8) to which the conductors are soldered. These small contact plates, which serve to transmit the electric current to the lamp filament, are preferably of copper, which metal solders well on to the conductors. These small plates are fitted friction-tight into their recesses by heavy pressure, and, if necessary, by the aid of some adhesive.

The cap is formed (see Figs. 7 and 8, which shows sections, at right angles to each other, of the finished cap) by inserting the compressed cardboard disk *c*—which has been produced by known means, such as those currently employed in making buttons—in such a way that the recesses *f* of the disk fit over the inner ends of the lateral gudgeons *b*. The collars or disks on said gudgeons are held tight, in their lower portion, between the metal socket and the carbon disk. The outer edge of the metal cap is then beveled into the groove *d* of the insulating disk, so that this latter is securely held and fixed in the cap, between the outer

bezel of metal and the gudgeons *b*. In this way the finished cap is obtained.

What I claim and desire to secure by Letters Patent is:—

45

1. Caps for incandescent electric lamps, having a shaped socket and an insulating disk forming the bottom of the cap, said insulating disk being of hardened cardboard, said socket being of aluminum, said metal 50 socket being tightened upon said disk, said disk being provided with diametrically opposite recesses, said cardboard disk allowing the metal of the socket to be tightened upon the disk, the latter being adapted to maintain its integral form under the tightening pressure, said socket having gudgeons 55 adapted to fit in said recesses.

2. Caps for incandescent electric lamps, having a shaped socket and an insulating 60 disk forming the bottom of the cap, said insulating disk being of hardened cardboard, said socket being of aluminum, said metal socket being tightened upon said disk, said disk being provided with diametri- 65 cally opposite recesses, said cardboard disk allowing the metal of the socket to be tightened upon the disk, the latter being adapted to maintain its integral form under the tightening pressure, said socket having 70 gudgeons adapted to fit in said recesses, said gudgeons having collars integral thereon adapted to fit and be held between said socket and disk.

In witness whereof, I have hereunto 75 signed my name in the presence of two sub-scribing witnesses.

AIMÉ MARIN.
